UNITED STATES PATENT OFFICE.

WILLIAM A. MUNDY, OF PHILADELPHIA, PENNSYLVANIA.

WATER-TRAP.

SPECIFICATION forming part of Letters Patent No. 431,384, dated July 1, 1890.

Application filed November 16, 1889. Serial No. 330,537. (No model.)

To all whom it may concern:

Be it known that I, WILLIAM A. MUNDY, a citizen of the United States, residing in the city of Philadelphia, State of Pennsylvania, have invented certain new and useful Improvements in Water-Traps, of which the following is a full, clear, and exact description, reference being had to the accompanying drawings, forming a part of this specification.

10 My invention relates to water-traps designed to prevent the egress of foul air from the discharge-pipe back to the water-basin, and has for its object the improvement in such device of the valve-seat and the automatic tight seating with certainty of the ball-valve; also of the construction and arrangement of the valve-chamber relatively to the inlet-pipe and discharge-chamber; and for these purposes it consists of the features hereinafter fully described.

Referring to the drawings, Figure 1 is a vertical sectional view, partly in front elevation, showing the construction of the valve-seat in the bell-shaped mouth of the inlet-pipe to the trap, the annular opening formed between the same and the dividing-wall between the lower shell or casing and the valve-chamber, and the location and arrangement within the former of inlet and discharge pipes. Fig. 2 is a transverse horizontal sectional view through the line *a b* of Fig. 1 with the ball-valve removed from its seat.

The apparatus is constructed as follows: The trap-pipe *C*, which conveys the water into the valve-chamber *F* and discharge-chamber *H*, which has its discharge end in the chamber *H* curved upward, is preferably cast integral with said chamber *H*, with its discharge-opening as nearly central therein as possible, and 40 of bell-mouth form or internally beveled to form a cup-valve seat. The said chamber *H* has a top covering *N*, preferably cast integral with it, and which is so arranged relatively to the discharge end of the trap-pipe *C* as to 45 form between the two an annular opening *D*. The edges of the covering *N* and the discharge end of the pipe *C* are ground to form a spherical valve-seat for the ball-valve *G*. The valve-chamber *F* is formed by a glass or metal covering secured air-tight to extended end of the discharge-chamber *H* by means of a screw-

joint or otherwise. The said covering *N* of the discharge-chamber *H* is preferably provided with an opening or air-passage *L*, (see both figures of the drawings,) in order that when the level of the water *w* falls below the point at which the ball *G* will rise from the cup-valve seat the tendency to a vacuum in the chamber *F*, caused by the exit or discharge of the water therefrom, will be overcome by the entrance of air through the opening *L*, and the discharging volume of water will carry the ball with celerity and certainty to its true position on its valve-seat, while should there afterward occur any backflow of water after the head of the discharge-column has fallen below the line of the valve-seat, a continuous suction or pressure thereby produced would tend to hold the ball-valve more firmly in its seat until released by a new column of water discharged through the pipe *C*, the action of the parts as described being to hold the ball-valve *G* in its seat during the whole time that there is no intervening column of discharging water passing through the annular opening *D* in the valve-seat, and cut off all connection with the inlet or discharge pipe *C*, leading upward to the basin *B*, which is attached to the pipe *C* or its connections by means of the joint *A*, or in any other usual and suitable manner. By the arrangement shown of the pipe *C* relatively to the discharge-chamber *H* and the covering *N* thereof, and of the construction and arrangement of the several parts of the apparatus, as described, I am enabled to provide a cheap and economical and yet effective and efficient water-trap in the chamber *H*, in which there will always be sufficient suction to keep the ball-valve *G* constantly in its improved seat, as described, 90 when the level of the water shall fall below an annular opening therein.

Having thus described my invention, what I claim as new, and desire to secure by Letters Patent, is—

1. In a water-trap, the combination, with a discharge-chamber provided with a top covering centrally recessed, of a curved pipe having its discharge end central therein and opening upward and so arranged relatively to said recess of the covering of the discharge-chamber as to form therewith an annular wa-

ter-passage and a valve-seat, a ball-valve, and an air-chamber inclosing the same and secured to said discharge-chamber substantially as described.

5. 2. In a water-trap, the combination, with a discharge-chamber provided with a top covering centrally recessed and having an air-passage therein, of a curved inlet-pipe having its discharge end central therein and opening upward and so arranged relatively to said recess of the covering of the discharge-chamber as to form therewith an annular water-passage and a valve-seat, a ball-valve, and an air-chamber inclosing the same and secured to said discharge-chamber, substantially as described.

3. In a water-trap, the combination, with an air-chamber and ball-valve, of a discharge-chamber II, having a covering N, provided with an air-passage L, and a curved inlet water-tube C central in said chamber and opening upward and arranged relatively to said covering N as to leave an annular passage between them and to form thereat a spherical valve-seat, substantially as described. 20

In testimony whereof I have hereunto affixed my signature this 15th day of November, A. D. 1889.

WILLIAM A. MUNDY.
